FIG. 1 is a top, front, right perspective view of an inductor
package showing the new design;

FIG. 2 is a bottom, rear, left perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken lines represent portions of the inductor package
in which the design is embodied that form no part of the
claimed design. The dot-dash broken lines in FIGS. 1-6
represent the boundary of the claimed design and form no
part thereof.
